Patented Mar. 28, 1972

223,214

STRINGED MUSICAL INSTRUMENT, SPECIFICALLY A UKRAINIAN BANDURKA

Walter J. Pelensky, 19C Manheim Gardens,
Philadelphia, Pa. 19144

Original design application Mar. 28, 1968, Ser. No. 11,179,
now Patent No. 216,331, dated Dec. 16, 1969. Divided
and this application June 3, 1969, Ser. No. 17,505

Term of patent 14 years

Int. Cl. D17—03

U.S. Cl. D56—1

Fig. 2

Fig. 1

Fig. 4

Fig. 3

Fig. 5

FIG. 1 is a perspective view of a stringed musical instrument, specifically, a Ukrainian bandurka (Ukrainian style of guitar), according to my new design;

FIG. 2 is a fragmentary perspective view, showing the peghead from a different angle;

FIG. 3 is a front elevational or face view;

FIG. 4 is a left side elevational view;

FIG. 5 is a right side elevational view.

Portions of the drawings are shaded to indicate contrast.

This application is a division of my copending application Ser. No. D. 11,179, filed Mar. 28, 1968, now Pat. 216,331, granted Dec. 16, 1969.

I claim:

The ornamental design for a stringed musical instrument, specifically a Ukrainian bandurka, as shown and described.
